UNITED STATES PATENT OFFICE

JAMES A. BAILEY, OF CHICAGO, ILLINOIS, ASSIGNOR TO ADDRESSOGRAPH COMPANY,
OF WILMINGTON, DELAWARE, A CORPORATION OF DELAWARE

PRINTING DEVICE

Application filed August 11, 1928. Serial No. 298,971.

This invention relates to printing devices of the kind which are adapted to be run through an addressing machine for making printing impressions and are stored in trays or drawers in accordance with a selected 5 classification system.

The object of the invention is to provide a printing device of simple construction and light in weight and comprising a removable 10 card and a removable printing plate which can be easily and quickly changed whenever required.

Another object of the invention is to provide a lightweight printing device comprising 15 a frame made of cardboard, fibre board or other suitably stiff and substantial material, a metal printing plate having type characters embossed thereon and an information card, the frame being provided with 20 retaining means of simple character whereby the plate and the card may be detachably mounted in the frame so that either or both may be changed easily and quickly without separating the device from the set or system 25 for any material length of time.

In the accompanying drawings illustrating a selected embodiment of the invention,

Fig. 1 is a front elevation of a printing device embodying the invention, parts there- 30 of being broken away.

Fig. 2 is a vertical sectional view on the line 2—2 of Fig. 1.

Fig. 3 is a transverse sectional view on the line 3—3 of Fig. 1 showing the card partly 35 withdrawn from the frame.

Fig. 4 is a sectional view on the line 4—4, Fig. 1 showing the plate partly withdrawn from the frame.

Fig. 5 is a perspective view of the frame 40 showing the slotted side edge thereof.

Referring to the drawings the frame of the printing device comprises a back 6, a skeleton mat 7 fastened to the face of the back and provided with an opening 8 for a 45 card 9 and an opening 10 for a printing plate 11. The frame may be made of cardboard, light fibre board, or other light material and in any desired size and shape.

The mat may be made of the same size as 50 the back and the opening 8 is located above

the opening 10 and separated therefrom by an integral strip 12. Filler strips are interposed between the mat and the back to space the mat slightly from the face of the back. A filler strip 13 is located at the top 55 of the frame between the mat and the back, a filler strip 14 is located between the strip 12 and the back, a filler strip 15 is located between the bottom of the mat and the back and a filler strip 16 is located between the left side of the mat and the back. These 60 filler strips may be made in one integral member, as shown in the drawings, or they may obviously be made separate parts if desired. The filler strips are fastened to the back and the mat is fastened to the filler strips by adhesive or by any suitable fastening means. The filler strips 13 and 15 are somewhat narrower than the top and bottom 65 parts of the mat, and the filler strip 14 is 70 somewhat narrower than the strip 12 so that the inner marginal edges of the top and bottom parts of the mat and both marginal edges of the transverse strip 12 will project 75 beyond the filler strips thereunder to form flanges 17 to receive the card and the plate. There is no filler strip between the mat and the back at the right end of the frame and the spacing of the mat from the back at this 80 end provides a slot 18 to receive the card 8 and a slot 19 to receive the plate. The mat is spaced sufficiently by the filler from the back to provide slots 18 and 19 of sufficient size to permit the card and the plate to be 85 easily inserted in and removed from the frame by endwise movement, and the flanges 17 constitute guides for the top and bottom edges of the card and plate and retaining means for holding the card and plate in the frame. It is not necessary to provide flanges 90 at the right end of the openings 8 and 10 because the flanges at the top and bottom of these openings will be sufficient to retain the card and plate but flanges similar to 17 may be provided at the left end of the 95 openings 8 and 10 in the same manner here- tofore described if desired. The printing device is simple in construction, it can be made strong and substantial of cardboard, fibre board or suitable paper material, or it 100

may be made of any other material suitable for the purpose. The card and plate may be inserted and removed from the frame easily and quickly so that changes can be made without separating the device from the set or system for any material length of time.

I am aware that changes in the form, construction, size and arrangement of the parts of my invention may be made without departing from the spirit or sacrificing the advantages thereof, and I reserve the right to make all such changes as fall within the scope of the following claim:

I claim:

15. A printing device comprising a frame made of cardboard or similar light material, a metal printing plate having printing characters embossed thereon in lines extending lengthwise of the plate, and a card having information thereon in lines extending lengthwise of the card, said frame having a continuous back, a mat of the same dimensions as the back and secured to the back and having a top, a bottom, two sides, openings to receive said plate and card, and a transverse strip between said openings, filler strips between the back and the top, bottom, one side and the transverse strip of the mat, the other side of the mat being spaced from the back to form slots through which the plate and card may be freely moved lengthwise thereof into and out of said openings, the inner marginal edges of the top and bottom of the mat and the top and bottom marginal edges of the transverse strip projecting beyond the filler strips thereof to form flanges at the top and bottom of said openings to retain the plate and card in place in the openings and in the frame.

JAMES A. BAILEY.
